FIRE DETECTION

Thomas Wossilek, P.O. Box 86, Library, Pa.

Filed July 14, 1958, Ser. No. 748,319

4 Claims. (Cl. 340—227)

This invention relates to fire detection and particularly to an apparatus and method by which the presence of fires can be detected at the inception. Every year many lives are lost and great property damage suffered by reason of fires which, if detected sufficiently early, could be controlled and the loss eliminated. There has been to my knowledge no inexpensive, easily installed apparatus or method for the early detection of fires. There have been proposed many sprinkling devices and systems designed to operate automatically after a fire has become sufficiently established to discharge heat enough to melt a metal closure in a sprinkling nozzle. These systems are expensive, unsightly and not adapted for use in homes and offices.

I have invented an apparatus and method for the detection of fires which is inexpensive, easily installed and effective for the early detection of fires before they have become established.

In a preferred embodiment, I provide first electrical contactor means in the area to be protected, said contactor means being movable upon expansion of the gases in the area, second contactor means spaced from the first contactor means and adapted to be touched by the first contactor means when said first means is moved by the expansion of gases, a source of electrical current connected to said first and second contactor means whereby contact of the two contactors completes an electrical circuit, and alarm means in the circuit actuated by the closing of the contactor means. Preferably, the alarm is a bell. In a preferred form, the first electrical contactor means is a light metal gate mounted in a housing in the wall of the area to be protected, and the second contactor means is a metal finger spaced from the first contactor means and in the path of its movement.

In the foregoing general description of my invention, I have set out certain objects, advantages and purposes of this invention. Other objects, advantages and purposes will be apparent from a consideration of the following description and the accompanying drawings, in which

Figure 1 is a diagrammatic illustration of a fire detection system according to my invention;

Figure 2 is an enlarged vertical section through a segment of the wall incorporating the contactor means of Figure 1;

Figure 3 is an enlarged vertical section through a wall incorporating a second embodiment of my invention;

Figure 4 is an enlarged vertical section through a floor segment incorporating the contactor means of the invention; and

Figure 5 is a schematic illustration of a third embodiment of my invention.

Referring to the drawings, I have illustrated a fire detection system comprising a housing 10 mounted in a wall 11 surrounding an area to be protected. The housing 10 is provided with a passageway 12 communicating through the wall, a gate or flap 13 preferably of aluminum or an aluminum alloy is hinged on hinge 14 mounted in electrical connection with conductor 15 which passes

2

through insulator 16 in the wall of housing 10. A contactor finger 17 is mounted in insulator 16 in the side wall of housing 10 spaced from the gate 13. Contactor finger 17 is connected to conductor 19. Conductor 15 is connected to one side of a source of electrical energy 20 and conductor 19 is connected to the opposite side of the source of electrical energy 20 through an alarm bell 21. When a fire occurs in the area 22, for example the left hand side of the wall 11 in Figure 2, the smoke produced by the beginning of the fire will cause an expansion of the gases in the room. These will seek to leave the room and will pass through the opening 12 in housing 10. This will cause the gate 13 to move against the finger 17 closing the electrical circuit from the source of energy 20. This in turn will ring the alarm bell 21 and warn the occupants or the fire department of the beginning of a fire. A holding relay 18 may be connected from conductor 15 to conductor 19 to give a steady alarm once the circuit has been closed.

In Figure 5, I have illustrated another embodiment of my invention using the detector apparatus of Figure 2. Since the embodiment illustrated in Figure 5 uses components which are identical with those of Figures 1 and 2, they will be given identical numbers. In the embodiment of Figure 5, the source of energy 20 is provided on opposite sides with conductors 15 and 19 as in the case of Figure 1. Gates 13 and conductor fingers 17 are placed in several areas to be protected. Each of the gates is connected in parallel to conductor line 15 through conductors 30, 31 and 32. Each of the conductor fingers 17 is connected to the conductor 19 by conductors 33, 34 and 35 in parallel through lights 36, 37 and 38. The lights 36, 37 and 38 may be placed together on a single panel mounted in a readily visible area. An alarm bell 21 is installed in conductor 19 in the fashion of Figure 1. A fire in any of the areas having the gate 13 and conductor 17 will cause the circuit to close which will light up the light in the particular circuit indicating the area of the fire and will ring the alarm bell 21 drawing audible attention to the presence of the fire.

In Figure 3 I have illustrated an embodiment identical with that of Figure 2 except for a pair of contactor fingers 17a and 17b, one on each side of gate 13 and connected by jumper 19a. Such a structure will be activated by a fire on either side of wall 39.

In Figure 4, I have illustrated a floor installation having a passage 40 between ceiling 41 and floor 42. A gate or flapper 43 is hinged to one side of the passage and normally rests on stops 44 in the closed position. In case of fire the smoke and heated gases will move into passage 40, raising gate 43 to contact finger 45, closing a circuit identical with that of Figure 1. A grating 46 is provided in floor 42 over passage 40 and a screen 47 in ceiling 41 to protect the contactor mechanism.

While I have illustrated and described certain preferred embodiments of my invention, it will be understood that this invention may be otherwise embodied within the scope of the following claims.

60 I claim:

1. In a fire detection apparatus for an enclosed area wherein an alarm means is actuated by a closing of a contactor means, the combination of said alarm means of a housing adapted to fit in the closure for the area, a 65 passage in said housing communicating through the closure, means hinged to one side of the interior of the passage and normally substantially closing said passage, a first electrical contactor means on said hinged means in the passage, said contactor means and said hinged means 70 being movable upon expansion of the gases in the area, second contactor means in the passage spaced from the hinged means and first contactor means in the direction

of egress from the enclosed area, and contacting the first contactor means when said first means is moved by the expansion of gases, a source of electrical current connected to said first and second contactor means whereby contact of the two contactors completes an electrical circuit, and alarm means in the circuit actuated by the closing of the contactor means.

2. A fire detection apparatus as claimed in claim 1 wherein the alarm means is a bell.

3. In a fire detection apparatus wherein an alarm means is actuated by a closing of a contactor means, the combination of said alarm means of a plurality of enclosed areas to be protected comprising a housing in the closure for each area, a passage in said housing communicating through the closure, means hinged to one side of the interior of the passage and normally substantially closing said passage, a first electrical contactor means on the hinged means in the passage, said contactor means and hinged means being movable upon expansion of the gases in the area, second contactor means in the 20 passage spaced from the first contactor means and hinged in the direction of egress from the enclosed area and contacting the first contactor means when said first

means is moved by the expansion of gases, a source of electrical current connected in parallel to each of said first and second contactor means in each passage, whereby contact of any two contactors completes an electrical circuit, and alarm means in each circuit actuated by the closing of the contactor means.

4. A fire detection apparatus as claimed in claim 3 wherein each alarm means is a light and wherein said alarm bell is fixed in series with all of the parallel circuits to be actuated on completion of any one thereof.
